UNITED STATES PATENT OFFICE.

LOUIS HEITZMANN, OF LONG ISLAND CITY, NEW YORK, ASSIGNOR TO HARRY J. SOHMER, DOING BUSINESS AS SOHMER & CO., OF NEW YORK, N. Y.

AUTOMATIC PIANO.

Application filed May 11, 1922. Serial No. 559,984.

To all whom it may concern:

Be it known that I, LOUIS HEITZMANN, a citizen of the United States of America, and a resident of Long Island City, borough 5 and county of Queens, city and State of New York, have invented certain new and useful Improvements in Automatic Pianos, of which the following is a specification.

My invention relates to automatic pianos, 10 and more particularly to that type commonly known as grand pianos capable of being played either manually or automatically at will. In pianos of this type, because of the peculiar and specific arrangement 15 and location of the elements comprising the playing essentials thereof, it has heretofore been considered necessary to effect the automatic playing of the piano through the medium of the manual keys, 20 with the result that the latter, during such automatic playing, not only presented an undesirable and constant movement but, because of the same, were subjected to excess wear and tear. The object of my invention 25 is to overcome these objections by providing a novel means which is operatively combined with the piano action in a manner to actuate the same, and which is common to both the manually operated piano keys and 30 the automatic mechanism and capable of being selectively operated by either. The operation of the piano action may thus be accomplished by the automatic mechanism or the manually operated keys independently 35 of each other, so that said keys are not affected by the operation of the automatic mechanism. Other objects of my invention will appear from the description hereinafter and the features of novelty will be pointed 40 out in the appended claims.

In the accompanying drawings, which illustrate an example of the invention without defining its limits, Figures 1 and 2 are fragmentary, sectional elevations of a piano 45 showing the parts in different positions, and Fig. 3 is a detail section on an enlarged scale.

In the drawings, 5 represents the keyboard of a piano of the type generally referred to as grand or square pianos, and 50 which is secured upon a suitable portion 6 of said piano preferably in a manner to be

readily disconnected therefrom. Action-brackets 7 are fixed upon the keyboard 5 in any suitable manner and support the hammer rail 8 and the wippen rail 9 in the 55 well known way, the two rails referred to being of a length suitable to the piano in which they are incorporated. Hammers 10 carried by shanks 11 are pivotally mounted upon the hammer rail 8 by means of flanges 60 12 fixed in position in any suitable manner, as by means of screws 13. The hammers 10 are arranged in registry with the piano wires 14, which are located in the piano in the customary manner, said hammers, in 65 their normal positions, resting upon a rest rail 15 through the medium of the shanks 11, as shown in Fig. 1. Wippens 16 of conventional form and construction are pivotally mounted upon the wippen bar 9 through 70 the medium of flanges 17 and are provided with flanges 16^a comprising pivotal supports for escapement levers 16^b arranged in operative relation to the hammers 10 and in engagement with knuckles 18 carried by the 75 shanks 11 of said hammers. It will be understood that the wippens include all of the parts customarily found in wippens adapted especially for grand or square pianos. Each wippen 16 projects outwardly 80 beyond the co-operating flange 17 and is pivotally connected by means of a link 19 with a jack 20 pivotally mounted by means of a flange 21 upon a rail 22 which is also fixed upon the keyboard 5. The jack 20 carries a back-check 20^a in operative relation to the co-operating hammer 10 and is further arranged to engage a damper lever 23 pivotally mounted by means of a flange 24 upon a support 25 extending upwardly 85 from the piano base 6 and provided at its upper end with a forwardly extending member 26, as shown in Figs. 1 and 2. A damper lever flange 27 is pivotally connected with the damper lever 23 and has adjustably mounted thereon the lifter wire 28 which passes slidably through the member 26 and at its upper end carries a damper 29 which may be of any usual and conventional form and co-operates 90 with the wires 14 in the well known way. A lever 30 is pivotally mounted at 31 upon

a flange 32 which depends from the wippen 16, as shown in Figs. 1 and 2, said lever 30, at its one end, being arranged to engage a suitable pad 33 or the like, carried by the 5 wippen 16, and at its other end being provided with a pad 34 adapted, under certain conditions, to engage a rod 35 extending parallel with the hammer rail 8. The piano further includes the customary bank of 10 manually operated keys 36 which are pivotally mounted upon the keyboard 5 and which operate in the well known way. In addition to the parts so far described, the piano is provided with automatically operating means for actuating the piano action, which means, in the illustrated example, comprise pneumatically operated bellows 37 suitably located in the piano and shown upon the piano base 6. It will be 15 understood that the bellows 37 are intended to be representative of automatic piano actuating mechanism generally and pneumatically actuated mechanism in particular, and that they are operated through the medium 20 of a perforated sheet in the conventional manner or in any other well known way.

The essentials of the present invention consist in providing a means operatively combined with the piano action or, more 25 specifically, with the wippen thereof, but preferably having no positive connection therewith and being common to both the manually operated keys 36 and to the automatically operating mechanism represented 30 by the bellows 37; this means or device, although it is operatively combined with the keys 36 and the automatic mechanism 37, has no positive connection with either, so that the keys 36 are not affected by the operation 35 of the bellows 37 and accordingly may be locked against movement when the piano is being automatically operated. In the illustrated example, the means or device referred to comprises a stem 38 extending 40 loosely through the key 36 and provided at its upper end with a head or pad 39 arranged to engage the lever 30. It will be understood that the lever 30 and its associated elements comprise parts of the soft pedal mechanism 45 and in some cases may be replaced by other arrangements; in such case the pad or head 39 of the stem 38 may be in direct engagement with the wippen 16. So far as the combination of the stem 38, or its equivalent, with the wippen is concerned, this lever 30 is therefore not required and may be dispensed with. At its lower end said stem 50 38 is provided with a head 40 arranged to engage a corresponding head 41 carried by 55 a rod 42 which is secured to the bellows 37. In the preferred arrangement the stem 38 extends slidably through the capstan screw 43, which is screw-threaded in the key 36 and is made of tubular form for the accommodation of the stem 38. A cushion 44 is

located at the upper end of the capstan screw 43 for the purpose of reducing and absorbing the impact forces resulting from an engagement of the capstan screw 43 with the head 39, as will appear more fully herein-after. Any suitable means may be provided for locking the keys 36 against operation when the piano is being automatically operated, such means being exemplified in the illustrated example by a member 45 70 hinged at 46 upon the keyboard 5. By bringing this member 45 to an upright position beneath the keys 36, as shown in Fig. 2, said keys are held against pivotal movement. 75

In the normal operation of the piano by means of the manually operated keys 36, the latter are depressed at their forward ends in the customary manner, whereby the rear ends thereof are lifted and the capstan screw 43 accordingly caused to exert a lifting action upon the head 39 of the stem 38. This lifting action is communicated to the lever 30 and by it to the wippen 16 or directly to the latter in cases where the lever 30 is omitted, and consequently brings about a pivotal movement of the wippen and its flange 16^a and escapement lever 16^b whereby the hammer shank 11 is pivotally actuated to cause its hammer 10 to strike the co-operating wire 14. As the wippen is actuated in the described manner, the link 19 will be moved downwardly and will cause the jack 20 to be pivotally operated to shift the back-check 20^a into an operative position, in which it performs its functions with respect to the particular hammer 10 in the well known way. The pivotal operation of the jack 20 also pivotally moves the damper lever 23 and accordingly, through the medium of the damper lever flange 27 and the lifter wire 28, raises the damper 29 away from the wire 14 to permit unrestricted vibration under the effects of the hammer blow. 100

When the piano is being automatically operated and the bellows 37 is collapsed, the rod 42 will be raised and in turn will lift the stem 38 and slidably shift the same in an upright direction relatively to the capstan screw 43 and to the key 36. This lifting of the stem 38 being communicated to the head 39 will operate the wippen and its co-operating parts in the same way as previously described to cause the hammer 10 to strike one of the wires 14. The operation of the stem 38 through the medium of the automatic mechanism, as represented by the bellows 37, is entirely independent of and produces no effect upon the keys 36, which accordingly may be locked against movement through the member 45 or its equivalent. From this it will be seen that the piano action, as exemplified by the parts herein shown and described, is capable of being 115 120 125 130

operated manually or automatically at will, the automatic operation being entirely independent of the manual operation, and the manual operation being without effect upon the automatic mechanism. Heretofore, as previously stated herein, it has always been considered necessary to bring about the automatic operation of the piano action through the medium of the keys which, as a result, were pivotally actuated throughout the automatic operation of the instrument, which resulted not only in unnecessary wear and tear upon the parts, but also presented an undesirable appearance because of the constantly moving keys. It will be noted that the back-check 20^a is operated through the medium of the wippen and is not carried and operated by the keys directly, as is usually the case. The lever 30, as hereinafter set forth, is a part of the soft pedal mechanism and in addition to its other functions, serves to prevent lost motion when the soft pedal of the instrument is depressed in the customary manner, this being a well known arrangement.

In its illustrated form, the device whereby the keys or the automatic mechanism are operatively combined with the piano action is so located that it may be removed from the piano with the keyboard 5 and with the parts carried thereby.

It will be noted that the device in question has no positive connection with the wippen and that while it is common to both the manually operated keys and the automatic mechanism, it has no positive connection with either of these elements. This results in an arrangement of maximum simplicity and efficiency without necessitating a careful positioning of the parts with respect to each other, and in addition provides a mobility in the instrument which would not be present if the parts were positively connected with each other. It will be understood that the stem 38 and its associated parts are intended to be representative of equivalent devices which, in square or grand pianos, provide for the operation of the piano action through the medium of the manually operated keys or the automatic mechanism independently of each other.

Various modification may be made within the scope of the claims without departing from the nature of my invention.

I claim:

1. In a grand piano, the combination of a manually operated key, automatic operating means, a piano wire extending in a direction substantially parallel with said key, a hammer extending in the same general direction as said key for striking said wire, and means extending through said key in operative relation to said automatic means and operated by either said key or said au-

tomatic means, one independently of the other for selectively actuating said hammer manually and automatically at will.

2. In a grand piano, the combination of a manually operated key, automatic operating means, a piano wire extending in a direction substantially parallel with said key, a hammer extending in the same general direction as said key for striking said wire, a wippen in operative relation to said hammer, and a device arranged to co-operate with said wippen but having no positive connection therewith and extending through said key in operative relation with said automatic means and having no positive connection with said device being operable by either said key and said automatic device, one independently of the other, for selectively actuating said wippen manually and automatically at will to operate said hammer.

3. In a grand piano, the combination of a piano action, a manually operated key, pneumatic operating means, and actuating means arranged to cooperate with said piano action but having no positive connection therewith and extending through said key in operative relation to said pneumatic means and having no positive connection with either, said actuating means being operable by said key and said pneumatic means, one independently of the other, for selectively operating said piano action manually and pneumatically at will.

4. In a grand piano, the combination of a piano action, a manually operated key, pneumatic operating means, a device extending slidably through said key and movable thereby to operate said action and being movable independently of said key by said automatic mechanism for operating said piano action, and a back-check mounted independently of said key and said piano action and operatively connected with the latter.

5. In a grand piano, the combination of a piano action, a manually operated key, pneumatic operating means, a device extending slidably through said key, means carried by the latter for moving said device to operate said piano action, and means connected with said automatic mechanism whereby said device is movable by the latter independently of said key to operate said piano action.

6. In a grand piano, the combination of a piano action, a manually operated key, pneumatic operating means, a tubular capstan screw adjustably mounted on said key, and a stem slidably mounted in said capstan screw and arranged to be operated by said key to actuate said piano action and adapted to be operated by said automatic mechanism independently of said key to operate said piano action.

7. In a grand piano, the combination of a wippen, and means carried by said piano action including a wippen, a manually operated key, pneumatic operating means for operating said key, pneumatic operating steam independently of said key to actuate means, a tubular capstan screw adjustably mounted on said key, a headed stem slidably mounted in said capstan screw and adapted to be operated by said key to actuate said
- 5 In testimony whereof I have hereunto set my hand.

LOUIS HEITZMANN.
